UNITED STATES PATENT OFFICE.

ALFRED COTTON, OF ST. LOUIS, MISSOURI, ASSIGNOR TO HEINE BOILER COMPANY, OF ST. LOUIS, MISSOURI, A CORPORATION OF MISSOURI.

WATER-TUBE BOILER.

Application filed March 16, 1920. Serial No. 386,226.

To all whom it may concern:

Be it known that I, ALFRED COTTON, a citizen of the United States, residing at St. Louis, Missouri, have invented a certain new and useful Improvement in Water-Tube Boilers, of which the following is a full, clear, and exact description, such as will enable others skilled in the art to which it appertains to make and use the same.

10 This invention relates to water tube boilers of the type that comprise a plurality of banks of upright water tubes connected at their upper ends to transverse steam-and-water drums.

15 The objects of the invention are to increase the efficiency of boilers of the type mentioned; obtain more complete combustion and eliminate smoke; produce drier steam; increase the steaming capacity without increasing the size of the boiler and simplify the construction of boilers of the type referred to.

20 The figure of the drawing is a vertical sectional view of a boiler embodying my invention.

25 The circulation in the regular Stirling boiler is upwards through the front tube bank into the front steam-and-water drum, through the water circulators to the middle steam-and-water drum, and downward through the middle tube bank to the mud drum. It is well known that the amount of water evaporated per unit of heating surface is enormously greater in those parts 30 of the heating surface exposed to radiant heat from the fire, than in those parts which are heated by impingement of hot gases only. It is also well known that, as a consequence of this, the greatest amount of water 35 evaporated per unit of heating surface takes place in the front tubes of the front bank in the regular Stirling boilers.

40 As the whole of the upward flow of the water in the usual Stirling boiler is into the front steam-and-water drum, and as the water circulators connecting the front steam-and-water drum with the middle steam-and-water drum are necessarily restricted in number and consequently in their total 45 cross-sectional area, the water tends to accumulate in the front steam-and-water drum. In other words, the water level in the front steam-and-water drum rises when the boiler is driven at even moderately high 50 rates, owing to the restricted flow area be-

tween the front and middle steam-and-water drums. Also owing to this restriction, the pumping action of the circulatory flow (or, more correctly, the pumping action which causes the circulatory flow) up the front 55 tube bank tends to slightly lower the pressure in the mud drum, so that the water level in the rear steam-and-water drum falls below the normal or average level. At high driving rates this effect is so marked that 60 the water level in the rear steam-and-water drum sometimes falls until it is a few inches below the bottom of the drum, thus causing the upper ends of the tubes in the rear bank 65 to become dry and overheated to such a degree that their expanded joints into the drum shell give trouble by leakage.

A further and a serious trouble with the ordinary Stirling boiler, caused by the rising of the water level in the front steam-and-water drum, is that in conjunction with the turbulent state of the water therein, caused by the whole upward flow of steam and water being concentrated into said front steam-and-water drum, a great deal of water 70 is carried over with the steam into the middle steam-and-water drum, and much of this water remains in suspension in the steam leaving the boiler by the outlet on the middle steam-and-water drum. Recognizing 75 this objectionable feature, inventors have sought to dry the steam by such means as placing the steam outlet on the rear steam-and-water drum, using this drum as a separating chamber; by carrying the steam to 80 the rear drum and back into a pocket or compartment in the middle drum, or by adding another drum above the three steam-and-water drums.

85 Another objection to the regular Stirling boiler is that the furnace gases rise immediately into the front tube bank, thus causing said gases to be chilled below their ignition point before combustion is complete and resulting in loss of efficiency and heavy 90 smoke. This objectionable characteristic has also been recognized by inventors who have sought to improve the facilities for combustion by placing a baffle at or near the front of the front bank of tubes, so as to cause 95 the gases to rise the full height of the combustion chamber before entering the front bank of tubes. This remedy is objectionable, in that this front baffle is not as easy 100 of access or construction, or as cheap to in- 105 110

stall, as are baffles simply laid on the back of the banks.

My invention improves boilers of the Stirling type by meeting and removing all of the disadvantages and objectionable characteristics above referred to in a very simple manner, and it provides an efficient and accessible boiler that can be constructed as cheaply as the regular Stirling boiler or even more cheaply. Broadly stated, my invention consists in arranging the tubes of a water tube boiler of the general type previously referred to in four distinct banks, each of which has a different function, and which may be called the radiant heat bank A, the convected heat bank B, the downcomer bank C, and the economizer bank D. The front bank or radiant heat bank A consists of only a few rows of tubes that are exposed to the radiant heat of the fire and of the combustion chamber X. In the preferred construction the radiant heat bank is formed by two rows of tubes which are the only tubes discharging into the front steam-and-water drum 1. In some instances three rows of tubes may be used in the radiant heat bank, but in all cases the cross-sectional area of the tubes of the radiant heat bank A will be less than the cross-sectional area of the tubes of the convected heat bank B. Since the flow of steam and water into the front steam-and-water drum 1 is very much less in my improved boiler than in the usual Stirling boiler, the water in the front drum of my boiler is much calmer. Consequently, I am enabled to make the front drum 1 smaller than is the usual practice and still get much better separation of the steam and water. As I have even more room for water circulators 2 between the front drum, and the middle steam-and-water drum 3 with less water to flow through said circulators 2 than in the regular Stirling boiler, there is less rise of the water level in the front drum, with further improvement in the separation of the steam and water. This improved separation of the steam and water or reduced tendency to carry water over with the steam from the front drum 1 into the steam space of the middle drum 3 allows my boiler to supply drier steam when driven at rates much higher than is considered reasonable practice with the regular Stirling boiler.

The second tube bank B of my boiler may be described as exposed to convected heat only. This second bank discharges directly into the middle steam-and-water drum 3, and though not necessary, I prefer to make this middle drum larger than is the usual practice in boilers of the Stirling type. I am enabled to do this without increase of the total cost of construction of the boiler, because I make the front steam-

and-water drum 1 smaller than usual, as already explained, and the rear steam-and-water drum 4 smaller than is the usual practice, as hereinafter explained. Since the water flowing up the second bank or convected heat bank B flows directly across the middle steam-and-water drum 3 without having to encounter the resistance to flow of any water circulators, as in the regular Stirling boiler, the flow to the third bank 75 or downcomer bank C of my boiler is free. Owing to the increased size of the middle steam-and-water drum 3, and to less water being carried by the steam passing from the front steam-and-water drum into the 80 middle drum through the steam circulators 2, the steam leaving the steam space of this middle drum 3 is much drier than in the usual Stirling boiler. So much is this the case that the steam outlet of my boiler may 85 be placed on the middle drum of the boiler. I prefer, however, to carry the steam from the middle drum to the rear drum, through circulators 5, to still further separate the entrained water from the steam and place 90 the steam outlet 6 on the rear drum 4 of the boiler.

The third bank of tubes C of my boiler is the downcomer bank. I have explained how the water enters this bank from the 95 middle drum 3 with very much less resistance than in the ordinary Stirling boiler.

The fourth or economizer bank D is connected between the rear steam-and-water drum 4 and a lower chamber 7 which may 100 either consist of a mud drum or a number of mud drums connected together in the usual manner. When a plurality of mud drums are used, it is essential, however, that the lower ends of the tubes of the second and 105 third banks B and C, respectively, be connected to the same mud drum, so as to permit the water that returns through the downcomer bank C to flow directly across the mud drum to the lower ends of the tubes 110 of the upcomer bank B without having to encounter the resistance to flow of any water circulators. As it is not good practice to allow very cold feed water to flow down the economizer bank D, as then some condensation of water vapor in the gases may take 115 place on the tubes, resulting in external corrosion, I prefer to connect a few water circulators 8 between the middle and rear steam-and-water drums 3 and 4, respectively. 120

The hot water flowing through these circulators mixes with and raises the temperature of the feed water sufficiently to avoid the trouble just mentioned. The flow through these circulators 8 also tends to prevent any 125 objectionable lowering of the water level in the rear steam-and-water drum 4, as already mentioned; but it must be remembered that, owing to the avoidance of nearly all the restriction to circulation present in the usual 130

Stirling boiler, by reason of all the circulating water having to pass through the water circulators, except that short-circuited by flow reversals within the tube blanks, the 5 lowering of the water level in the rear steam-and-water drum 4 of my boiler is small and unobjectionable, even, at very heavy rates of driving. As the steam which enters the rear steam-and-water drum 4 of 10 my boiler is much drier than that leaving the middle drum of the usual Stirling boiler, much less steam space in the rear drum is necessary for further drying; and as there is much less fluctuation of the water level in 15 this rear drum, as just explained, I am enabled to make it smaller than usual with consequent reduction in the cost of construction. The baffles of the boiler can be arranged in various ways without departing 20 from the spirit of my invention, and while I have herein illustrated only one form of baffling means, I wish it to be understood that it is immaterial how the baffles of the boiler are constructed or arranged, so long as the 25 boiler is equipped with four banks of water tubes combined with a mud drum and three steam-and-water drums, or equivalent devices, in such a manner that the water in the first bank of tubes will circulate upwardly through same into the front steam-and-water drum, and the water in the second bank of tubes will circulate upwardly 30 through same into the middle steam-and-water drum and then through said middle drum to a third bank or downcomer bank of 35 tubes which lead to the mud drum. In the form of my invention herein illustrated a front baffle 9 extends upwardly from the mud drum 7 at the rear side of the radiant 40 heat bank A, the upper end of said baffle being spaced away from the front drum 1, as shown in the drawing. A second baffle 10 extends downwardly from the middle drum 3, between the second and third banks B 45 and C, respectively, to a point in proximity to the mud drum 7, and a third baffle 11 extends upwardly from the mud drum at a point between the third and fourth banks, the upper end of said third baffle 11 terminating at such a point that a space is provided 50 for the passage of the gases into the last tube bank D down which the gases travel to an outlet 12.

A most important advantage resulting 55 from my novel arrangement of tube banks, is the way in which a spacious hot combustion chamber X is naturally provided without any awkward devices or complicated baffling means in said chamber, it being possible with my boiler to support the front baffle 9 by the rear tubes of the radiant heat bank A. The simplicity of the baffling, the ease with which it is erected, and its accessibility are indicated clearly in the drawing, 60 which also shows how the spaces between the tube banks for access to the tubes are naturally formed. By laying the first baffle 9 on the back of the front tube bank, as is done in the usual Stirling boiler, the much desired first upward pass of the gases 70 through a hot combustion chamber is attained, and by having the front bank consist of a small number of rows of tubes, which is an essential feature of my invention, the gases are not unduly chilled during the first pass, while the temperature of 75 the combustion chamber is sufficiently reduced by the presence of the tubes of the front bank to avoid undue wear and tear of brickwork and furnace parts.

It will be seen that my invention does not consist in merely a splitting up of existing tube banks. Thus, my first and second banks are not attained by simply dividing the front tube bank of the usual Stirling boiler, for 80 this would not accomplish the highly important result of reducing the flow of steam and water to the front drum, and consequently, relieving the congestion in the water circulators between the front and 85 middle steam-and-water drums. It would not reduce the lift of the water level in the front drum and would not reduce the tumult in the front drum; and by failing to accomplish these results, it would not reduce the 90 amount of water carried over by the steam flowing from the front drum into the middle steam-and-water drum. It would not enable the front steam-and-water drum to be made smaller, and it would not avoid 95 the objectionable lowering of the water level in the rear steam-and-water drum, due to the restriction caused by the steam circulators between the front and middle steam-and-water drums being congested. It will 100 also be seen that my invention does not consist in merely a splitting up of the middle tube bank of the usual Stirling boiler into two banks, for this would also fail to accomplish any of the results mentioned in the last 105 paragraph. The only effect of this would be to make two gas passes instead of one, with each pass over a small bank of tubes, and would not in any way remove the objections which lie against the Stirling front bank, or, 110 indeed, make any change in it whatever.

Having thus described my invention, what I claim as new and desire to secure by Letters Patent is:

1. A water tube boiler, comprising at least two elevated transverse steam-and-water drums, water circulators connecting said drums together, a transverse mud drum, a radiant heat bank of upflow tubes leading upwardly from said mud drum to one of said elevated drums and constituting the sole source of water supply to said elevated drum, a separate and distinct convected heat bank of upflow tubes spaced away from said radiant heat bank and connected to the other 120

5 elevated drum for causing the remainder of the water rising from said mud drum to circulate upwardly to said other elevated drum, a baffle arranged between said radiant heat bank and said convected heat bank, a co-operating baffle for causing the fire gases to flow downwardly among the tubes of the convected heat bank, and downcomer tubes leading from one of said elevated drums directly to said mud drum.

10 2. A water tube boiler, comprising three elevated transverse steam-and-water drums, water circulators connecting the front drum with the middle drum, a transverse mud drum, a radiant heat bank of upflow tubes leading upwardly from the mud drum to the front steam-and-water drum and constituting the sole source of water supply to said front drum, a separate and distinct convected heat bank of upflow tubes leading upwardly from the mud drum to the middle drum for causing the remainder of the water supplied to said mud drum to circulate upwardly to said middle drum, a baffle arranged 15 between the radiant heat bank and the convected heat bank, downcomer tubes leading from the middle drum to the mud drum, and an economizer bank of tubes leading from the rear steam-and-water drum to the mud drum.

20 3. A water tube boiler, comprising three elevated transverse steam-and-water drums, steam-and-water circulators connecting the front drum with the middle drum and the middle drum with the rear drum, a transverse mud drum, a radiant heat bank of upflow tubes leading upwardly from the mud

25 drum to the front steam-and-water drum and constituting the sole source of water supply to said front drum, a separate and distinct convected heat bank of upflow tubes spaced away from the radiant heat bank for conducting the remainder of the water supplied to the mud drum upwardly to the middle steam-and-water drum, a baffle arranged between the radiant heat bank and the convected heat bank, a co-operating baffle for causing the fire gases to flow downwardly among the tubes of the convected heat bank, downcomer tubes leading from the middle steam-and-water drum to the mud drum, and an economizer bank of tubes leading from the rear steam-and-water drum to the mud drum.

30 4. A water tube boiler, comprising at least two elevated transverse steam-and-water drums, a transverse mud drum, a radiant heat first bank of upflow tubes leading from the mud drum to the front steam-and-water drum and arranged at the rear of the combustion chamber outside of the main path of flow of the gases, water circulators connecting said elevated steam-and-water drums together, a convected heat second bank of upflow tubes leading from the mud drum to the second steam-and-water drum for causing the remainder of the water rising from the mud drum to pass directly into said second steam-and-water drum, a baffle between the first and second banks, and downcomer tubes leading from the second steam-and-water drum directly into said mud drum.

ALFRED COTTON.
